(57) **CLAIM**

The ornamental design for a portion of dragline bucket, as shown and described.

DESCRIPTION

FIG. 1 is a front perspective view of an embodiment of a portion of dragline bucket showing my new design.

FIG. 2 is a front elevational view thereof.

FIG. 3 is a rear elevational view thereof.

FIG. 4 is a right-side elevational view thereof; the left-side elevational view being a mirror image.

FIG. 5 is a top view thereof; and,

FIG. 6 is a bottom view thereof.

In the figures, broken lines represent environmental subject matter and form no part of the claimed design, while dotted lines represent the border between claimed and unclaimed subject matter and form no part of the claimed design.
